His attorney.

UNITED STATES PATENT OFFICE.

CHARLES B. RAWSON, OF WORCESTER, MASSACHUSETTS.

MAKING MATCH-SPLINTS.

SPECIFICATION forming part of Letters Patent No. 298,502, dated May 13, 1884.

Application filed February 23, 1883. (No model.)

To all whom it may concern:

Be it known that I, CHARLES B. RAWSON, a citizen of the United States, residing at Worcester, in the county of Worcester and State 5 of Massachusetts, have invented a new and useful Improvement in Friction-Matches, of which the following is a specification, the invention being illustrated in the accompanying drawings, in which—

10 Figures 1 and 2 show my improved method of preparing the match-splints; Fig. 3, the match-splints attached to the paper, and Fig. 4 a detached match-splint.

Similar letters refer to similar parts in the 15 several views.

My invention relates to an improved mode of preparing the match-splint, and also the mode of attaching the same to a strip of some suitable connecting material; and it consists 20 in partially or entirely severing a "card" of wood or other suitable match material on lines running obliquely to the sides instead of at right angles to the same, so the match-splint, when severed from the card, will be wedge-shaped, the end forming the match being the base and the opposite end the apex; also, in 25 attaching the card of splints to a strip of paper, leather, or other suitable material and rolling the same, thereby bringing the paper 30 between the matches so the matches as rolled will not come in contact.

I prepare the card A of wood or of any suitable match material, and form the notches A' A' on two opposite sides, leaving sufficient 35 space A'' A'' to form the "head" of the match. I then sever the card by means of thin chisel-shaped blades, or in any other known method, on the lines a a a a, running diagonally across the card, or at oblique angles to the notched sides, forming a wedge-shaped splint, the head A'' forming the base and the opposite end, b, the apex. The notches A' A' can be placed opposite each other, as in Fig. 1, when the lines a a will run from a notch 40 on one side to a notch next to the opposite notch on the other side, and the lines a a will then be parallel; or the notches on one side may be placed opposite the match-heads on the other side, as shown in Fig. 2, in which 45 case each alternate line will incline in the opposite

direction to the notched sides of the card. By this method of forming the splints only one-half the amount of material is required for the same quantity of matches as by the method in common use.

55

The heads of the matches are prepared with some paste or composition capable of igniting by friction, as in the case of matches now in use. The card is then placed upon a strip of paper, leather, or any similar material, C, and 60 attached to the same at its central section, as at c c c c, Fig. 3, by glue or any suitable adhesive substance, applying it preferably to a narrow strip, so as the splints are separated from the card they may be readily detached from the 65 strip of paper C. The strip of paper should be at least as wide as the matches are long, or it may be slightly wider than the card of matches, as shown in Fig. 3, so as to better protect the igniting ends of the matches, and 70 the strip of adhesive material should be applied to the center of the match-card and for about one-fourth of its width. The card and attached paper C are then rolled together, thus bringing the paper between the matches 75 and forming a very compact and tasteful shape for the market, and especially convenient for use. In cutting the splints on the lines a a, they should be severed almost across the card, leaving only a sufficient space to hold the 80 splints together until they are attached to the strip of paper C. If found more convenient, the match-card may be attached to the paper before the igniting composition or paste is applied to the match-heads.

85

I do not claim forming notches on two opposite sides of the match material, as that has been heretofore done, and is shown in Letters Patent to H. Reiman, November 7, 1865, No. 50,843; neither do I confine myself to any particular mode of forming said notches or of severing the splints on the oblique lines, as any of the well-known methods of making match-splints may be readily adapted to the manufacture of my improved form of splint; but 90

What I do claim as my invention, and desire to secure by Letters Patent, is—

1. A card of match material having two opposite sides notched to form the match-heads, and being nearly separated on oblique lines, 95 100

forming splints, so the pointed end of one splint shall come between the heads of two adjacent matches, as described, and for the purpose set forth.

- 5 2. The process of making a card of match-splints, consisting of forming notches on opposite sides of a card of match material, leaving a space between the notches to form the match-head, and afterward partly severing the 10 splints from the card on lines obliquely to the notched sides, so the splints will be wedge-shaped, having the point of each match lying between the heads of the two adjacent matches, as and for the purposes specified.
- 15 3. The combination, with a card of match-splints, of a strip of paper, leather, or similar material, attached to the splints at their cen-

tral section by means of some suitable adhesive substance, as and for the purpose set forth.

4. As an article of manufacture, a roll or 20 package of friction-matches, consisting of a card of cuneiform match-splints, the point of one splint lying between the heads of the two adjacent splints, the several match-splints having some suitable igniting compound attached 25 to their larger ends, and being attached at their central section by any suitable adhesive substance to a strip of paper, leather, or similar connecting material, as and for the purpose set forth.
